UNITED STATES PATENT OFFICE

CLYDE W. MARTIN, OF LITTLE ROCK, ARKANSAS, ASSIGNOR OF ONE-HALF TO
LEONARD E. HOFFMAN, OF ST. LOUIS, MISSOURI.

PORTABLE GROCERY-STORE.

1,379,463.

Specification of Letters Patent.

Patented May 24, 1921.

Application filed June 18, 1920. Serial No. 329,908.

To all whom it may concern:

Be it known that I, CLYDE W. MARTIN, a citizen of the United States, residing at Little Rock, in the county of Pulaski and State of Arkansas, have invented certain new and useful Improvements in Portable Grocery-Stores, of which the following is a specification.

This invention relates to traveling stores and more particularly to portable automobile grocery stores.

The object of the invention is to provide a motor driven vehicle equipped with a body in the form of a store having a self service system and in which the driver also performs the duties of checker and cashier so that no other attendants are required.

Another object is to provide an apparatus of this character having a compartment arranged for canned and bottled goods to prevent them from falling over or shaking out of position during transportation.

Another object is to provide an apparatus of this character with a refrigerator constructed and arranged for advantageous use with stores of this character.

Another object is to provide an apparatus of this character having a simple and efficient entrance and exit and so arranged that the driver may remain in his seat and yet perform the duties of a checker and cashier for customers leaving the store.

With these and other objects in view, the invention consists of certain novel features of construction as hereinafter shown and described and then specifically pointed out in the claim, and in the drawings illustrative of the preferred embodiment of the invention.

60 In the accompanying drawings:

Figure 1 represents a longitudinal section of a store constructed in accordance with this invention.

Fig. 2 is a horizontal section taken on the line 2-2 of Fig. 1.

Fig. 3 is a transverse vertical section taken on the line 3-3 of Fig. 1.

Fig. 4 is a side elevation of a trailer adapted for use in connection with a store of this character.

Fig. 5 is a rear elevation thereof.

Fig. 6 is a detail horizontal section showing compartments for holding bottled and canned goods to insure them against upsetting, and,

Fig. 7 is a similar view showing a spring arrangement to hold articles in position.

In the embodiment illustrated the store 1 constituting this invention is shown mounted on a motor vehicle chassis C having the usual wheels W, engine E covered by the ordinary hood H.

The store 1 is in the form of a closed vehicle body the side walls 2 of which are surmounted by a peaked roof 3 although obviously this roof may be of other construction if desired.

In one side wall 2 near the front of the vehicle body 1 are entrance and exit openings 4 and 5, respectively, separated by a railing 6 the exit opening being arranged adjacent a driver's compartment 20 having the usual seat S adjacent one end of which is positioned a table or shelf 21 which forms one side wall of the exit opening and is for a purpose presently to be described.

The entrance and exit openings 4 and 5 are communicatively connected with a central aisle 8 extending longitudinally of the body 1 at the rear of the driver's compartment a common turnstile 7 forming a closure between the openings 4 and 5 and the aisle 8 as is shown clearly in Fig. 2.

At the rear of the body 1 is a refrigerator

9 which may be of any desired construction opening into the aisle 8 so that customers

may have ready access thereto. Extending longitudinally on opposite sides of the aisle 8 and spaced from the floor thereof

are two shelves 10 below which are formed open bins 11 with drawers 12 mounted

over the bins on the shelves and of a width less than the shelves as is shown clearly in

Figs. 2 and 3 so that a customer may use the shelves 10 to support a basket or other container into which the articles to be purchased may be placed.

The drawers 12 are provided with any suitable hand grips shown at 12^a to assist in opening and closing them and arranged over them are

containers 13 for bottled and canned goods said containers having upstanding front walls 13^a with vertical intersecting partitions 14 therein to form compartments to

receive the canned and bottled goods and to prevent said goods from upsetting or

being shaken off the shelf or compartment during transportation.

Arranged above the compartments 13 are a plurality of horizontally disposed longi-

tudinally extending vertically spaced shelves 16 divided into compartments 15 by upright or vertical partitions 17. These compartments may contain goods of various character to be exhibited for sale and are easily accessible to purchasers who enter the aisle 8 through the entrance 4 and after selecting the goods desired pass out through the exit 5 being retarded in their passage by the 10 turnstile 7 which causes them to stop opposite the table 21 so that the driver may check up the goods and receive the cash to cover the cost thereof.

A closure 18 for the entrance and exit 4 15 and 5 is made in the form of a door hinged to open downwardly and having on its inner face cleats or steps 19 so that purchasers may easily enter and leave the store. When the store is moving from place to place it is of 20 course understood that this closure will be fastened upward in operative position to exclude dust and dirt from the interior of the store.

At one side of the refrigerator 9 is a compartment 22 which may be used for a bread 25 closet or for anything else desired.

If found desirable trailers as 23 may be used in connection with the main body 1 and connected therewith by tongues or similar connectors 24 the front ends being closed by doors 25 which permit when open entrance to the interior of the trailer. This trailer is intended as a stock room from which the depleted stock in store 1 may be 35 replenished. It also may contain commodities in case lots which are intended to be used as leaders.

While this improved store 1 is shown equipped with a self service system above 40 described it is to be understood that all modern and convenient labor saving devices may be used in connection therewith the peculiar arrangement of the entrance and exit adjacent the driver's compartment 45 eliminating the necessity of employing a clerk or checker and enables the driver to

perform these duties without leaving his seat.

In the use of this store the driver may make daily or weekly trips from one location 50 to the other or he may go as often as he pleases to the different localities and after stopping his vehicle at any desired point will open down the door 18 to permit customers from surrounding territory to enter 55 and purchase the desired goods. The period of time which he will remain at one locality of course will be controlled by circumstances and he will pass from place to place according to conditions.

60 This improved store will be a great convenience to housekeepers enabling them to purchase their supplies right at their door.

The preferred embodiment of the invention is disclosed in the drawings and set 65 forth in the specification, but it will be understood that any modifications within the scope of the claim may be made in the construction without departing from the principle of the invention or sacrificing any 70 of its advantages.

What I claim is:

A portable automobile store including a compartment having a central aisle with article supporting means on opposite sides 75 thereof, a driver's compartment at the front corner of said store, a customer's entrance and exit passages parallel with each other at the corner opposed to said driver's compartment and opening through the side of the 80 main compartment, the exit passage being arranged adjacent the driver's compartment with a cash counter and checking table between it and said compartment whereby the driver may serve as a chauffeur, a checker 85 and a cashier and a common turnstile across the inner ends of said passages controlling said entrance and exit.

In testimony whereof I affix my signature hereto.

CLYDE W. MARTIN.
